DESIGN FOR A DEFLECTOR GUARD FOR TOILET SEAT

Charles Epstein and Earl R. Neuberg,
Hollywood, Calif.

Application March 11, 1944, Serial No. 112,877

Term of patent 7 years

(Cl. D4—5)

To all whom it may concern:

Be it known that we, Charles Epstein and Earl R. Neuberg, citizens of the United States, residing at Los Angeles, in the county of Los Angeles and State of California, have invented a new, original, and ornamental Design for Deflector Guard for Toilet Seat, of which the following is a specification, reference being had to the accompanying drawing, forming part thereof.

Figure 1 is a plan view of a deflector guard for toilet seat showing my new design.

Figure 2 is a sectional view on line 2—2 of Figure 1 looking in the direction of the arrows.

Figure 3 is a front view in elevation, and Figure 4 is a side view in elevation of the deflector guard for toilet seat in Figures 1 and 2.

We claim:

The ornamental design for a deflector guard for toilet seat, substantially as shown.

CHARLES EPSTEIN.
EARL R. NEUBERG.
